FIG.11

FIG. 1 is a front elevational view of a refrigerator cabinet for kegs of beverage showing my new design;

FIG. 2 is an elevational view taken from one side thereof;

FIG. 3 is a rear elevational view thereof;

FIG. 4 is an elevational view taken from the side opposite that shown in FIG. 2;

FIG. 5 is a top plan view thereof;

FIG. 6 is a bottom plan view thereof;

FIG. 7 is a front elevational view of a modified form of the refrigerator cabinet for kegs of beverage shown in FIG. 1;

FIG. 8 is an elevational view taken from one side of FIG. 7;

FIG. 9 is an elevational view taken from the side opposite that shown in FIG. 8;

FIG. 10 is a front elevational view of FIG. 7, with the doors removed; and

FIG. 11 is a front perspective view of the refrigerator cabinet, with the doors removed and the top in a raised position.

The broken line representation of kegs in FIG. 11 is for purposes of illustration only.

I claim:

The ornamental design for a refrigerator cabinet for kegs of beverage, as shown and described.
